UNITED STATES PATENT OFFICE.

AUGUST C. JACOBI, OF SAND CREEK, WISCONSIN.

ELEVATOR-ALARM.

SPECIFICATION forming part of Letters Patent No. 268,105, dated November 28, 1882.

Application filed October 21, 1882. (No model.)

To all whom it may concern:

Be it known that I, AUGUST C. JACOBI, of Sand Creek, Dunn county, Wisconsin, have invented a new and useful Improvement in Elevator-Alarms, of which the following is a full, clear, and exact description, reference being had to the accompanying drawings, making a part of this specification, in which—

Figure 1 is a perspective view of an elevator-box with my improvements attached. Fig. 2 is an elevator with one side of the casing removed. Fig. 3 is a transverse vertical section through *x x* of Fig. 1. Fig. 4 is a perspective view of the driving-wheel with the rocker-arm attached. Fig. 5 is a detached view of the rocker-arm. Fig. 6 is a section of the driving-wheel, showing the slot through which the rocker-arm works. Fig. 7 is a detached view of the crank-lever for operating the alarm. Fig. 8 is a detached view of the alarm mechanism.

My invention has reference to elevators used in mills for raising grain and other mill-stuff; and it consists in devices for giving an alarm whenever the elevator stops from clogging or other cause. Elevators are liable to stop from clogging and other causes. Sometimes they are overloaded with grain or other mill-stuff. Sometimes the buckets get loose on one side and catch on the elevator-legs. It is also well known that gas in greater or less quantities is always present in elevators, and when the elevator stops without being noticed the driving pulley or wheel continues to revolve, and by friction with the belt will heat, cause fire and explosion. To prevent such disasters is the object of my present invention.

To enable others skilled in the art to make and use my invention, I will proceed to describe the exact manner in which I have carried it out.

In the drawings, A represents an elevator-casing; B, the elevator-belt passing around the cylinder C and the driving-wheel D, which have their bearings in the casing A. The driving-wheel is provided with a slot, *d*, in the rim, for a purpose hereinafter explained.

The rocker-arm E is loosely pivoted upon the extension of the spokes, so that its rim may fit in and pass through the slot *d* in the rim

of the driving-wheel, as shown in Fig. 2. The inner end of the rocker-arm is bent at right angles to form a crank, for a purpose hereinafter explained.

The coil-spring F is attached at one end to the rim of the driving-wheel, and its opposite end to the rocker-arm, as shown in Fig. 2, so that when the bent end of the rocker-arm is carried toward the shaft of the driving-wheel the coil-spring is extended, and when the bent end is released it is drawn again in its normal position by the contraction of the spring. This rocker-arm, extending through the slot and a small distance beyond the surface of the driving-wheel, is necessarily brought in contact with the elevator-belt B.

It is evident from this description that while the belt is moving with the driving-wheel no effect is produced upon the rocker-arm E; but when the elevator-belt ceases to move, from any cause whatever, friction is brought to bear upon the rocker-arm, which causes it to move upon its pivot and throw back the bent portion or crank *e*. Thus by means of friction with the belt B and the coil-spring F the crank *e* is caused to vibrate. When the friction is on, the crank moves toward the center of the driving-wheel, and when the friction is relieved the coil-spring draws it toward the periphery. I will now suppose the elevator-belt to be arrested in its course from clogging or other cause. Friction is immediately brought to bear upon the rocker-arm E, which throws the crank *e* toward the shaft of the driving-wheel, bringing the crank in contact with the short arm of the bent lever G, which is moved around one-quarter of a circle, at the same time raising the outer arm, *g*, through one-quarter of a circle. The lever is then released and allowed to resume its normal position until the next revolution of the wheel, when this operation is repeated, and will be continued as long as the band is stationary and producing friction on the rocker-arm E.

To the outer arm of the bent lever G is attached a rod or cord, H, the opposite end of said cord being attached to the coil-spring I, as shown in Fig. 1. To this coil-spring is attached the alarm-bell J.

The operation of my device is as follows: 100

Whenever, from any cause, the elevator ceases to operate, the friction of the belt upon the rocker-arm E causes the bent portion e of that arm to come in contact with the bent lever G, and that in turn causes the outer end of that to rise and ring the bell as long as the driving-wheel revolves and the elevator-belt fails to operate; but as soon as the elevator resumes its operation the rocker-arm would be relieved from friction, bent lever G would remain undisturbed, and the alarm-signals would cease to be given.

In order that the bent lever G may be at all times in the proper position to be caught and moved by the crank e it has its bearing in the adjustable plate K, as shown in Fig. 1, and by means of this adjusting-plate the bearing and position of the bent lever F is readily adjusted.

Having thus fully described my invention, what I claim as new, and desire to secure by Letters Patent, is—

1. In an elevator-alarm, the driving-pulley

C, provided with a slot, d, in its rim, in combination with the pivoted rocker-arm E, provided with a rim passing through the slot d, 25 and having its inner end, e, bent into a crank at right angles to the plane of its motion, substantially as herein described.

2. In an elevator-alarm, the driving-pulley C, provided with the slot d in its rim, and carrying the pivoted rocker-arm E, provided with the crank e, in combination with the bent lever G, having its bearing in the adjustable plate K, substantially as and for the purpose set forth. 30

3. The driving-pulley C, carrying the rocker-arm E, in combination with the bent lever G, cord H, and alarm mechanism, substantially as and for the purpose set forth. 35

AUGUST C. JACOBI.
